UNITED STATES PATENT OFFICE

2,564,228

DRUM FOR TIME CONTROLLED MECHANISM

Earl H. Pitney, Minneapolis, Minn.

Application April 5, 1945, Serial No. 586,776

1 Claim. (Cl. 74—568)

1

This invention relates to time control mechanisms and more particularly to drum structures for use in said mechanisms.

The invention relates to a time control device which can be utilized in any apparatus where a change in a control unit is desired to take place at certain predetermined intervals. It can be used in connection with mechanical or electrical time controlled mechanisms and it is being shown and described herein in connection with time controlled mechanism for automatically selecting desired radio programs over an extended period of time. It might conveniently be used in connection with time controlled radio tuning apparatus such as disclosed in my prior Patents Number 2,322,387, issued June 22, 1943, and Number 2,172,623, issued September 12, 1939.

In my prior patents I have disclosed a control drum which is spun or otherwise formed with an integral side wall having a plurality of helically arranged perforations adapted to receive projecting pins which can be placed in desired perforations to actuate the remainder of the control mechanism. The drums disclosed in my prior patents have been found expensive to manufacture due to difficulty and expensive machinery required to perforate the side wall of the drum with the hundreds of holes required to produce a mechanism which will operate over a period of one week for example.

It is a general object of the present invention to provide a control drum for time mechanisms which is much more practical and inexpensive to manufacture and which at the same time will have the same degree of accuracy as those drums mentioned above.

More particularly it is an object of the invention to provide a drum including a simply and cheaply constructed cage upon which is mounted a sheet or strip of material in which the pin receiving perforations can be formed without requiring expensive special machinery therefor.

Another object of the invention is to provide a control drum in the form of a cage having the perforated sheet or strip placed therearound, wherein the cage per se is relatively light and unstable but the sheet or strip which is placed around it will bind the entire structure together to produce a strong, light drum unit.

The above and other objects and advantages of the invention will more fully appear from the following description made in connection with the accompanying drawings, wherein like reference characters refer to the same parts throughout the views, and in which:

2

Figure 1 is a generally diagrammatic plan view of a time controlled radio receiver embodying my invention;

Figure 2 is an enlarged longitudinal sectional view through the drum;

Figure 3 is an enlarged perspective view, partially exploded, of the drum with part of the helical strip broken away;

Figure 4 is a fragmentary exploded view of a different form of drum cage; and

Figure 5 is a fragmentary detail of a portion of the helical strip showing one type of anchoring pin which can be used therewith.

In Figure 1 there is shown in general and without any detail a time controlled radio receiver such as disclosed in my prior Patent Number 2,322,387. A radio receiving set is indicated at 6 and an electric clock is shown at 7. The main clock shaft 8 drives a large gear 9 which in turn rotates a shaft 10 upon which a control drum 11 is slideable but keyed thereto to rotate therewith. A feed screw 12, the groove of which is engaged by a follower pin 13 is adapted to cause the drum 11 to move from left to right as the clock shaft 8 and drum shaft 10 rotate, as disclosed in said Patent Number 2,322,387.

Within the rectangle indicated by the dash line 14 is trip means and radio tuning mechanism actuated by a resilient storing drive element 15 driven by a shaft 16 which receives its power from the clock 7. The trip mechanism in the rectangle 14 includes 3 trip levers 17 whose ends are adapted to engage pins 18 which are selectively and removably positioned in apertures 19 formed in the circular wall on the drum 11. Thus far the general mechanism is as disclosed in Patent Number 2,322,387, and will not be explained in detail herein.

As stated above it is the object of the present invention to provide an improved structure for the control drum 11 whose rotation with the pins 18 therein causes the trip levers 17 to be actuated.

In Figures 2 and 3 there is shown a cage including a pair of disk-like end pieces 20 having a series of notches 21 formed around their edges. Extending between the end pieces 20 are relatively closely spaced thin flat longitudinal members 22 which have sufficient resilience to flex rather readily. The longitudinal members 22 have notches 23 formed closely adjacent their ends and the notch ends of said longitudinal members are adapted to interlock with the notched portions 21 of the end pieces 20. If desired, the ends of the longitudinal members 22

may be welded to the end pieces 20 but it is also possible and preferred that the notches 23 be of such width as to frictionally engage the end pieces 20 to hold the cage together during the assembly of the complete drum.

Wound helically about the cage made up of the end pieces 20 and longitudinal members 22 is a strip 24 having the apertures 19 formed therein. As shown in the drawing, the apertures 19 are provided in spaced rows longitudinally of the strip 24, and it will also be seen that the apertures lie in rows longitudinally of the drum structure.

As illustrated in the drawing the edges of adjacent convolutions of the strip 24 about one another and the ends of the strip may be bent over adjacent longitudinal members 22 and secured thereto by any suitable means such as spot welding as indicated at 25 in Figure 3.

When the strip 24 is wound about its supporting cage it will be seen that the longitudinal members 22 will be held in close engagement with the disc-like end pieces 20 and the resulting structure while light in weight is a simple and extremely rigid drum unit.

The pins 18, one of which is shown in detail in Figure 5 are adapted to be selectively placed in any of the desired openings 19 in the strip 24. As disclosed in my prior Patents Number 2,322,387 and Number 2,172,623, the trip levers 17 will not be actuated until the rotation of the drum 11 brings one of the pins 18 into contact with one of the trip levers.

Formation of the strip 24 is considerably cheaper than the formation of a drum such as disclosed in my prior patents since it can be quickly and easily stamped on a punching machine to produce the large number of apertures required for automatic tuning a radio receiver for a period of one week. The strip 24 is shown with three rows of holes formed therein. Regardless of the number of the rows of holes it is clear that the strip can be fed through the punching machine at a relatively rapid rate and the holes can be punched at predetermined intervals as the strip is fed. It is then a simple matter to wind the strip on its supporting cage and by reason of the predetermined spacing of the holes longitudinally of the strip 24 the finished drum will present straight lines or rows of holes longitudinally of the drum with such exactitude that positive and accurate control is achieved.

In Figure 4 there is shown a detail of a different form of cage structure. It shows a portion of a cage end piece 26 having spaced apertures 27 formed about its edge portion. Instead of the flat longitudinal rods 22, as shown in Figure 3, there is illustrated a plurality of round bars 28 having reduced ends 29 which fit into the apertures 27 in the end piece 26. The reduced ends 29 extend through the end piece 26 and can be turned over to prevent them from slipping out of the end piece. The punched helical tape 24 can then be wound around the cage thus formed in the same manner as described in connection with the structure in Figures 2 and 3.

In both cage constructions it should be understood that the longitudinal members 22 and 28 are comparatively narrow and should any of the short projecting pins 18 engage one of the longitudinal members, said members will be sufficiently flexible to shift slightly and permit insertion of the pins 18.

From the foregoing description it will be seen that I have provided a simply constructed drum for use in time controlled mechanism which has the advantage of easy and low cost manufacture, and while it is made of relatively thin, light parts the complete drum unit has sufficient stability and rigidity to operate successfully and accurately. It is a drum structure which is particularly suited for mass production and will greatly reduce the overall cost of manufacturing all types of time controlled units to which it is adapted and particularly automatic tuning mechanisms for radio receivers.

It will, of course, be understood that various changes may be made in the form, details, arrangement and proportions of the various parts without departing from the scope of my invention.

What I claim is:

A pin carrying drum comprising a pair of drum heads, a plurality of circumferentially spaced laterally flexible stretchers extending between said drum heads and fastened thereto, and a strip wound helically over said stretchers to form a drum wall, said strip having a series of control stations at predetermined intervals along its length and each of said control stations being constituted as a plurality of spaced apart pin-receiving apertures located crosswise of the strip.

EARL H. PITNEY.
